UNITED STATES PATENT OFFICE.

WILLIAM ARBUCKLE HARVEY, OF SCRANTON, PENNSYLVANIA

ELECTRIC FIXTURE.

Application filed August 18, 1919. Serial No. 317,255.

To all whom it may concern:

Be it known that I, WILLIAM A. HARVEY, a citizen of the United States, residing at Scranton, in the county of Lackawanna and State of Pennsylvania, have invented certain new and useful Improvements in Electric Fixtures, of which the following is a specification.

As heretofore practised, various means have been provided in an electrically-equipped building for accommodating or attaching electrical appliances, such as vacuum cleaners, electric irons, extension cords for portable electric lamps, and other like devices. Most common among the means for attaching such appliances to a suitable source of electricity, are the flush type base board or wall receptacles, which are used primarily because they may be more or less obscurely placed. At the same time, they are expensive to install, particularly where the house is wired after it has been completely constructed. In many instances, surface type receptacles are set on the wall, in which event they often take the form of an attachment for wall fixtures. The idea is to provide a wall or floor receptacle, making it unnecessary to remove the light bulb from a fixture when it becomes desirable to attach a vacuum cleaner or other form of appliance. As stated, the flush type floor receptacles are expensive to install; this is also true of the flush type wall or base receptacles. And another consideration makes it desirable to improve the form of receptacle which is used in connection and as an attachment for a so-called permanent wall or ceiling bracket. All receptacles of the surface type are constructed with a comparatively large mounting base, which covers an unnecessarily large area of the wall or ceiling surface, to a decided disadvantage when the wall or ceiling is to be repapered. Not only this, but these conventional forms of receptacles are so constructed as to make it practically impossible or undesirable for the one papering the wall to remove the receptacle in order that he may fit the paper evenly around its supporting base and produce a neat job.

The present invention has for its primary object to provide a plug attachment for so-called permanent electric wall and ceiling fixtures, which is not only capable of exceedingly cheap production, but is also capable

of enabling the wall to be repapered and the paper to be distributed around the supporting base of the receptacle in a neat manner, to which end one feature of the invention consists in providing a relatively narrow mounting base for the plug and to so construct the associated parts of the mounting base that they may be readily removed without subjecting the mechanic to the danger of charged wires. Thus, it will be an inducement to him to remove the associated parts of the mounting base and properly fit the paper around the narrow mounting base in keeping with its proper distribution over the wall or ceiling.

While the above recited object and advantages of the present invention are involved in the principal features of construction, there are other improvements which make the present construction more acceptable than those now in use. For instance, by a slight modification the invention may be constructed as an individual receptacle or socket fixture, in which event it may be installed independently of a permanent wall or ceiling fixture.

A still further object consists in constructing the device contemplated by the invention of standard parts, whereby it will of course have a universal use. In this connection, the parts and arrangement of the parts are such as to meet the approval of the underwriters as to proper installation and insulation.

Further objects will appear upon reference to the accompanying drawings and the following detailed description of the same, the novelty involved being particularly pointed out in the subjoined claims.

In said drawings—

Fig. 1 is a perspective view of a conventional form of wall bracket or fixture (shown in dotted lines), with the preferred form of the invention attached thereto;

Fig. 2 is a vertical section of the preferred form of the invention;

Fig. 3 is a sectional view on the line 3—3 of Fig. 2; looking in the direction of the arrows;

Fig. 4 is a vertical sectional view of the mounting base and its associated parts;

Fig. 5 is a view similar to Fig. 2, but slightly modified, particularly in the manner of supporting the canopy. (In this form, as well as in the following forms, the in

block which is supported on the mounting base is of porcellaneous material, whereas the insulating block in the forms just described is of fibrous material).

5 Fig. 6 is a sectional view on the line 6—6 of Fig. 5;

Fig. 7 is a view similar to Fig. 4, but showing the insulating block of the porcellaneous material;

10 Fig. 8 is a plan view of the interior construction of the fixture;

Fig. 9 is a vertical section of a modified form, involving practically the same features of construction as Fig. 2, with the exception that the insulating block is of the porcellaneous material and the fixture is constructed for individual attachment to the wall;

Fig. 10 is a sectional view on the line 20 10—10 of Fig. 9;

Fig. 11 is a sectional view on the line 11—11 of Fig. 10; and

Fig. 12 is a view similar to Fig. 11, with the exception that the conductor wires are not shown and the anchoring means for the socket terminal contact plate, consisting of the screws, are riveted to the side of the terminal contact plate, instead of being engaged by nuts.

30 Referring now to the drawings in detail, particularly to the drawings shown in Figs. 1 to 8, inclusive, A represents the common form of wall bracket or fixture, having the usual canopy B adapted to cover the terminal contacts and conductor wires, the usual mounting base, etc. It is common for houses equipped with electricity to have these forms of wall fixtures. Now, when it is desirable to further equip a building with socket

40 or plug fixtures for accommodating electrical appliances, they are sometimes attached to these wall brackets. But, as previously stated, their design and construction are inadequate. By the present invention it

45 is proposed to construct the attachment for these wall brackets with an exceedingly narrow, elongated mounting base 1, preferably constructed of fibrous insulating material, adapted to be mounted in juxtaposition to the bracket A by a plurality of screws 2 received in the countersunk openings in the mounting base. While three screws are shown as the medium for securing the base to the wall, ordinarily two, or even one,

55 would be sufficient, but three are provided should any one of them fail to be placed in a position to engage a solid base in the plaster construction. In attaching the invention to the wall fixture, the canopy B of the

60 fixture is recessed to receive the protruding end 1^a of the mounting base. The conductor wires 3 are adapted to be connected in any suitable manner to the bracket conductor wires; they preferably extend longitudinally of the mounting base 1 and enter

the protruding end 1^a thereof through openings made to receive them, which openings terminate in the top surface of the base, with the wires extending through the termination of the openings to the terminal plates or brackets of the socket attachment, the details of which will be hereinafter described. Supported by the mounting base

1 is an insulating block 4, constructed of any suitable insulating material, preferably fibrous or porcellaneous. This insulating block is of the same width as the mounting base, the lower end of which lies flush with the lower end of the mounting base, but the opposite end terminates at a point considerably below the protruding end 1^a of the base.

75 This insulating block is constructed with a stepped portion 4^a, providing a pair of shoulders on the opposite ends of the block, as at 4^b, whereby suitable screws 4^c may be employed in securing the insulating block to the base 1. Attached to opposite

80 sides of the insulating block 4 are the terminal plates 5 for attaching the ends of the conductor wires 3. One of these plates extends substantially the height of the insulating block 4 and is secured thereto by a pair of screws 5^a having their ends embedded in the fiber of the block. The end of this

85 plate terminates in a resilient contact 5^b, and the plate on the opposite side provides an attaching clip for the shell socket 6. This clip preferably comprises a horseshoe-shaped end 5^c, made to substantially conform to the shape of the bottom of the socket

90 shell 6, suitable screws 6^a being employed to mount the socket shell and the clip on the insulating block. In some instances it may be desirable to construct the shell with openings in its opposite sides, in which event the

95 clip 5^c will overlie the bottom of the socket shell. However, should the clip underlie the bottom of the socket shell, only one opening will be necessary in the side of the shell 6,

100 this one to receive the end 5^b of the clip on the opposite side of the insulating block. Suitable screws 5^d may be employed for attaching the ends of the conductor wires to the contact plates. Now, when the plug is

105 screwed into the shell 6, the part 5^b of one clip and the bottom of the shell attached to the end 5^c of the other clip will form the

110 necessary terminal contacts.

As is customary in fixtures of this kind, a canopy 7 is used to cover the terminal connections. However, in the present instance, this canopy is recessed, as at 7^a, to permit the end 1^a of the mounting base 1 to protrude through the canopy. It is pre-

115 ferred that the recess 7^a be cut in the vertical wall of the canopy and in the periphery thereof. The opening is of such a size as to snugly fit the mounting base. In some instances it would be desirable to confine the

120 canopy in place by means of an annular

sleeve 8, having threads corresponding with the threads of the socket shell 6, with which it is adapted to engage, the sleeve being provided with an intermediate enlargement 5 and reduced ends, the inner of which adapted to have a wedging effect between the narrow throat of the canopy and the socket shell 6, whereby the canopy may be held in place and insulated from the shell and other 10 parts of the fixture construction. If need be, the canopy may be lined with insulating material, such as 7^b. Furthermore, a suitable insulating collar 8^a may be used to overlie the insulating block and the terminal 15 connections. A still further insulating precaution may be resorted to, such as the ring-shaped piece 8^b, which is adapted to be inserted between the edge of the canopy and the wall. It is preferably constructed with 20 a depression or groove to receive the edge of the canopy, and a portion of its rim is cut away so as not to interfere with the protruding end 1^a of the mounting base. A suitable tab, such as 8^c, is provided as an 25 abutment for the inside of the vertical wall of the canopy, which will prevent displacement of the ring should the edge of the canopy become unseated from the groove.

Referring now to the features of construction of the forms illustrated in Figs. 5 to 30 8, inclusive, the same general idea is carried out, with the exception that the insulating block 4 is of a porcellaneous material, and for this reason it will be necessary to so arrange the screws 6^a so that their 35 threaded ends may be engaged by suitable nuts, with their head portions embedded in recesses in the block. This method is resorted to because it is impractical to thread 40 the porcellaneous material in a manner to obtain a firm seating of the screws. Of course, in the case of the screws 4^c, which fasten the insulating block to the mounting base, no change will be necessary, as their threaded 45 ends may be effectively fastened in the fibrous material of the mounting base. It will be noted that in this form a different means is employed for securing the canopy in place; instead of the sleeve 8, a pair of 50 brackets 9 are fastened under the screws 4^c, which extend outwardly with downwardly turned ends, having openings therein, registering with suitable openings in the side of the canopy, also with openings in the insulating lining 7^b, suitable screws 9^a being 55 used to attach the canopy to the bracket. When this attaching means for the canopy is employed, the insulating lining 7^b should extend to the edge of the narrow throat portion 60 of the canopy and separate the canopy from the shell 6. It is to be also noted that the screws 5^a for securing the contact plate 5 to the insulating block in this form are provided with nuts. It is also preferred to 65 confine the nuts in square recesses in the

insulating material, of substantially the same dimensions as the nuts, to prevent the nuts from turning.

In the form illustrated in the Figs. 9 to 12, inclusive, either the porcellaneous or fibrous material may be used for the insulating block, and either of the two forms of screw attaching means may be employed, according to the material used, and the canopy may be secured either by the sleeve 8 or the 75 brackets 9. But as the fixture in this form is intended to be used independently of any associated bracket fixture, the mounting base 1 is slightly modified to meet this requirement, to which end, instead of constructing 80 it with a protruding end 1^a, its length is reduced and the insulating block 4 is supported thereon in a manner to leave extensions 1^b on opposite sides of the insulating block. In these instances suitable screws 2^a are 85 countersunk for securing the mounting to the wall or ceiling. The insulating ring 8^b need not be recessed to accommodate the protruding end 1^a of the mounting base, but it may take the form of an uninterrupted annular ring grooved to receive the edge of the canopy, as in the other forms. Now, in 90 this form the conducting wires will lead direct from the wall or ceiling, and instead of coming through the mounting base they 95 may be brought in on opposite sides of the mounting base and the insulating block and fastened to the contact plates 5 (see Fig. 11).

It will be readily seen that not only is the 100 device extremely simple in construction and capable of being produced, with a slight modification, of standard equipment, but the feature of providing the mounting base of such a narrow width will enable a sufficient area of the wall to be covered around the fixture which will prevent any danger of ragged edges or like defacement of the wall to be seen after the canopy is secured in place.

Claims:

1. An electric fixture having a relatively narrow mounting base of insulating material, an insulating block supported on said base, means on said block for securing a socket connection, means for receiving the ends of the conductor and completing a circuit to said socket connection, a canopy cover for said fixture, said narrow mounting base and conductor protruding through the side of the canopy cover and adapted to cooperate with another electric fixture, with the said conductor in circuit with said other fixture, and an insulating piece comprising an annular ring underlying the canopy of the first-named fixture, having a recessed or 115 cut-away portion through which the protruding end of the narrow mounting base passes and a tab or detent adapted to bear against the inside of the opposite side of the canopy cover.

2. An electric fixture having a relatively narrow mounting base of insulating material, an insulating block supported on said base, means on said block for securing a socket connection, means for receiving the ends of a conductor and completing a circuit to said socket connection, an insulating cover

for said socket and insulating block, a canopy cover for the fixture, a pair of brackets carried by said insulating block adapted to engage the canopy cover and fasten it to the fixture, and an insulation between the canopy and the socket connection.

WILLIAM ARBUCKLE HARVEY.
